UNITED STATES PATENT OFFICE

PHILIP L. HAIMS, OF CLEVELAND, OHIO

SOUND-PRODUCING INSTRUMENT

Application filed April 28, 1930. Serial No. 447,938.

This invention relates to sound producing instruments, and is in the nature of a toy or simple musical instrument for producing different tones by means of a vibrating metal 5 reed or strip.

In one form means are provided for varying the effective length and consequently the pitch of the reed, so that it is possible to play a simple tune on the device.

10 It is intended that the reed should be struck by the finger or other object to start its vibration, and a sounding box may be associated with the reed to increase the volume of sound.

15 Fig. 1 is a perspective of one form of the invention. Fig. 2 is a perspective of another form. Fig. 3 is a perspective of a detached reed. Fig. 4 is a section of the stop bar shown in Fig. 1.

20 Referring to Fig. 1, 10 indicates a sound box of any suitable shape or material, with a screened opening 11 at one end if desired. Mounted on the top of this box is a reed 12 of thin spring metal, which is fastened at 25 one end to the top of the box as indicated at 13. This reed is bowed upwardly out of contact with the top of the box, and its free end projects beyond the side of the box and is provided with a weight 25 to decrease the 30 rapidity of the vibrations. This weight may be tapped by the finger or other object to start the vibration of the reed, which will thus sound a note which will be amplified by the sound box.

25 To vary the effective length of the reed I provide a stop or choke bar 14 extending across the same, and capable of being adjusted lengthwise of the reed. The ends of this bar 14 are held on screws 15 by means 35 of nuts 16 pressing the ends of the bar against springs 18 coiled around the screws above a roller washer 19 held by a screw 20. Each screw 15 is slidable in a slot 17 in a block 23 fastened to the top of the box at each 45 end thereof, the bar 14 extending through a slot 30 in the side of the block, and the roller 19 traveling in an undercut groove along the bottom of the block.

After starting the vibration of the reed 50 12 its tone may be varied by grasping the

nuts 16 and moving the bar 14 back and forth, which will vary the pitch accordingly.

In the form shown in Fig. 2 a sound box is indicated at 27, and the reel 24 is fastened to the top thereof and may be vibrated in a 55 similar manner, over the opening 29 into the box. In this form the choke bar is omitted, and the reed may be choked by pressing the finger thereon.

In the simple form shown in Fig. 3 the reed 60 21 is portable and it may be placed on the edge of a table or on any box and held at one end by the finger piece 22 while the other end is struck and vibrated. And obviously the hand may be used to choke or vary the 65 effective length of the reed.

I claim:

1. A sounding instrument comprising a sounding box, a vibrating reed extending 70 across the box and fixed at one end thereto, the other end being free and projecting beyond the side of the box, a stop bar movable along the reed, and guides on the box, for the opposite ends of the stop bar.

2. A sounding instrument comprising a 75 sounding box, a vibrating reed extending across the top of the box and fixed at one end thereto, the other end of the reed being free, and the reed being bowed upwardly 80 out of contact with the top of the box, a stop bar extending across the reed in contact with the upper side thereof, said stop bar being movable laterally to vary the effective length of the reed, and adjustable fastenings between the opposite ends of the stop bar and 85 the top of the box.

In testimony whereof, I do affix my signature.

PHILIP L. HAIMS.
